UNITED STATES PATENT OFFICE.

JOHN D. RIPSON, OF THOROLD, CANADA.

DESIGN FOR A BURIAL-CASKET.

SPECIFICATION forming part of Design No. 21,339, dated February 9, 1892.

Application filed January 4, 1892. Serial No. 417,036. Term of patent 7 years.

To all whom it may concern:

Be it known that I, JOHN DANFORD RIPSON, of the town of Thorold, in the county of Welland, in the Province of Ontario, Canada, 5 have invented and produced a new and original Design for Burial-Caskets, of which the following is the specification, reference being had to the accompanying drawing, forming part thereof.

10 The figure is a perspective top view of a casket, which view I deem sufficient to fully illustrate my design.

The leading features of my design consist in the ornamental corrugated corners of the 15 head and foot panels and the ornamental moldings inclosing the said panels, extending between the corner-pieces, as at C and D, the head and foot panels being indicated at A and B. The central panel c is raised and has

diagonally-corrugated ends extending inwardly a short distance. The edges of the lid E are ornamented by a continuous line of ornamentation. The base of the casket has also a continuous line of ornamentation extending around it, and has pedestals *f* at intervals extending around the side and ends of the body. On these pedestals are supported flaring columns, as shown. Extending from column to column around the body of the casket are arches. 20 25 30

What I claim is—

The design for a burial-casket, herein shown and described.

JOHN D. RIPSON.
